A. MUDGE.
SMUT MACHINE.

Patented Feb. 25, 1836

Feb 25, 1836

Abraham Mudge. Canajoharie. New York.

Petition for Patent

The Apparatus referred to in the Letters Patent and making part of the same consisting of a description in the words of the said Abraham Mudge himself of his improvement in the machine for separating straw and other impurities from grass.

To all to whom these presents shall come, Be it known that I, Abraham Mudge of Canajoharie in the County of Montgomery, and State of New York, have invented a new and useful machine for separating, and other impurities from straw and other kinds of grass, and that the following is a full and exact description of the construction and operation of the said machine as invented by me.

Take the center of a iron shaft (of about three feet in length & one & a half inches in diameter) turned and fitted for running in an upright position) place a circular plate of cast iron ten inches in diameter and of sufficient thickness to fasten firmly on the shaft. This plate is provided with eight or more wings or flanges, projecting one inch moreover above and below the plate and extending two inches beyond the edges of the plate. The wings or flanges on the under side occupying the spaces between the wings or flanges on the upper side & the wings or flanges may be connected after they project beyond the plate & from its half the number of wings, described above but double them with the shaft with the circular plate and wings or flanges around them and all balanced ^{the} load on a conical frame fitted to receive it with weights, brass, &c. &c. The plate and wings are then surrounded by a comb of cast iron or iron wire of such diameter that the space between the wings and the inner surface of the comb will be about one inch. The comb of cast iron is furnished with a projection from the inner surface about one third of an inch and terminating half an inch from the lower edge or bottom of

Feb 25, 1836

The curb, and about two inches apart, as if the curb is made of sheet metal may be perforated with small holes so the curb may be made of stone. — The depth is height of the curb is such that the wings will be about one third of an inch from the floor on which the curb rests, and the same distance from the curb. of the curb rests on a floor of cast iron that is now and is covered at top also with cast iron sheet iron. Near the centre of the curb is an opening to admit the grain into the machine. And through the floor on which the curb rests, and near the outer side is also an opening of about three inches long and one and one half inches wide for the purpose of allowing the grain to escape. On the inner shaft and at a convenient distance below the bottom of the curb is a wind wheel of about fourteen inches diameter and about five inches in depth is enclosed in a case of thin sheet iron having two places of discharge, one of two ports or places of discharge, direct to the grain as it escapes from the machine above. The grain as it escapes from the curb is conducted by a short spout into the current of air set in motion by the wind wheel which current of air is unimpeded and free to fall from the short spout into a narrow spout placed to receive it standing on an inclination of about fifty degrees elevation through which the wind drives the dust &c and the grain descends into a receiver below. The short wind spout or place of discharge for wind is on the opposite side of the machine and the wind is conducted upwards to the opposite side of the curb by means of a spout or conduct, and this is located across the rear of the curb and made to pass through the grain before it enters the machine for the purpose of separating dust &c from the grain. There is also one or more openings through the curbing of the curb near the outer edge and spouts attached thereto for the purpose of allowing several dust to escape from the machine. The machine is set in motion by means of a fly wheel and turns at the rate of about one hundred revolutions, per minute. The grain having entered through

covering of the curb over the curb is thrown by the wings or flanges attached to the circular plate, against the curb and its projections attached thereto with sufficient force to break the small balls and disengage them and other impure substances which adhere to grain and to dislodge passing quickly across the curb until it reaches the opening in the floor on which the curb sits and is conducted by the curb itself into the current of grain in motion by the wind wheel before described. - - - of machines of the kind described above incision will clean from eight to twelve bushels of grain an hour. When a machine is required to perform more business. The dimensions are to be enlarged in proportion to the amount of business required to be performed, and the number of the circular plates with wings or flanges (proportioned to the dimensions of the curb to be used) are to be placed on the curb. The wings on the uppermost plate alternating or occupying the spaces between wings on the plates beneath them. The principles which I claim to have applied to the process of cleaning grain from a curb and other impure substances by means of the machine above described, and which application I claim to have invented and which I believe to be new and useful is that of throwing the grain by means of wings or flanges attached to a circular plate as above described against some hard substance with sufficient force to break the small balls &c &c

And whether the plate be circular or any other form as when throwing, flanges be of any other form or shape I have described. The invention of attaching wings or flanges to a plate of cast iron or of any other substance for the purpose of cleaning grain & other impure substances off the curb of the curb with ribs projecting inward from the inner surface whether made of cast iron or any other material I also claim as my invention. The wind wheel action with curb or flanges as aforesaid either of the claim is part of my invention and the wind wheel with the places of discharge throughout the course I also claim as part of my invention.
